WINDOW WASHING MIXTURE
FOUNTAIN BRUSH

Mark Soss, Spokane, Wash.

Application November 12, 1946, Serial No. 709,206

1 Claim. (Cl. 299—84)

1 My present invention relates to implements in the general class of brushing, scrubbing and cleaning, and more specifically to an improved window-washing mixture fountain brush of the type wherein the liquid cleansing agent or soap and water are pre-mixed in desired quantities before being distributed to the bristles of the brush for cleansing operations.

The primary object of the invention is the provision of a hand manipulated brush composed of a minimum number of parts that may with facility be manufactured at low cost of production, and the parts assembled with facility to insure a cleansing implement that may be handled with facility and which is effective in the performance of its functions.

Figures 1 and 2 of the drawings show a plan view and an enlarged longitudinal sectional view respectively of a utility brush especially designed for car washing, and window washing.

Figures 3 and 4 show respectively a plan view and a longitudinal sectional view of a hand brush embodying the invention, and used for toilet purposes; and

Figure 5 is a sectional view of the head portion of a brush for bath and massage purposes in which the invention is physically embodied.

In the accompanying drawings I have illustrated several embodiments of my invention in which the parts are combined and arranged in accord with means so far devised for the practical application of the principles of the invention; but it will be understood that further changes and alterations may be made in these exemplifying drawings and mechanical structures within the scope of my claims without departing from the principles of the invention.

In the window washing brush of Figs. 1 and 2 the bristles or tufts of the brush are mounted in a perforated, flat, circular bottom wall 2 of rubber or other suitable material, and this wall is fashioned with multiple ports 3 that extend through the wall from an interior space 4 that forms a mixture-discharge chamber above the bottom wall 2.

The mixture-discharge chamber is closed by a cover plate 5 of suitable metal and circular shape, and the cover plate co-acts with a crown plate 6 to form a liquid soap container separated by its bottom plate 5 from the discharge chamber.

The circular crown plate is provided with an integral annular flange 7 that encloses the edge of the plate 5 and the edge of the circular head, the metal parts being welded and suitable means

being provided to cement the head within the flange, to insure water tight joints.

The flat cover plate 5, at its center is equipped with a short tube or pipe 8 forming a discharge nozzle, for the pre-mixed liquid, opening into the mixture discharge chamber 4, and one end of the tube is closed by the wall of a tube or pipe 9 extending parallel with the plane of the brush head, and closed at one end by a screw plug 10 to form a liquid soap chamber. The tube or pipe 9 forms a tubular handle for the brush and a portion of the handle forms a water reservoir, while the outer end of the handle is equipped with a cylindrical slide cap 11 closed at its outer end by a plug 12.

The handle-tube passes transversely through the walls of the crown plate forming the liquid soap container, with the joints welded, and the handle tube is welded to the transverse discharge tube 8, to provide a rigid structure between the handle and the brush head. For supplying water to the water chamber within the tubular handle an inlet port 13 is provided through a nipple, and an attaching nut 14 is employed 25 for connecting a water supply hose to the handle reservoir, the outer end of which is formed by a transverse partition 15 mounted within the tubular handle.

The partition provides a slide bearing for a slide rod 16 which is mounted to reciprocate longitudinally within the tubular handle and the outer end of the slide rod is equipped with a head 17 in which a screw 18 is threaded, and the screw which projects through a slot 19 in the tubular handle, is fixed in the slide sleeve 11, so that the sleeve may manually be reciprocated to push and pull the slide rod.

Within the tubular handle the slide rod is equipped with a pair of transversely arranged circular heads 20 and 21 loosely mounted on and reciprocable with the slide rod, and these spaced heads form disk valves for controlling a water inlet port 22 and a liquid soap inlet port 23 that open into the mixture discharge nozzle 8 through which the slide rod passes.

These loosely mounted disk valves arranged to close inwardly at the opposite sides of the ported nozzle are alternately opened and closed by a push and pull action of the slide sleeve 11, and for this purpose the slide rod is equipped with a pair of spaced heads 24 and 25 fixed on the slide rod with springs 8 coiled about the rod and interposed between valve 20 and head 24 and between valve 21 and head 25. The springs 55 initially close the valves, a push on sleeve 11

3

opens valve 20, and a pull on the sleeve opens valve 21; when valve 20 is opened liquid soap from the liquid soap chamber enters the tubular handle through ports 26 and thence passes through open port 23 into the discharge nozzle; and when valve 21 is opened water passes from the tubular handle or water reservoir through port 22 into the nozzle. The water and liquid soap are thus collected and mixed in the mixing chamber 4 from which the mixture passes through ports 3 to be distributed to the adjoining portions of the brush.

A spacer or separating sleeve 27 is rigidly mounted on the slide rod between the two spaced disk valves for alternate co-action with the disks in their opening movements, and a squeegee 28 is mounted on the crown plate of the brush head to facilitate washing, scrubbing, or cleansing windows.

In the toilet or hand brush of Figs. 3 and 4 the brush tufts or bristles 1 are mounted in a rectangular head 2 of rubber or other suitable material, and the head is provided with multiple ports 3 from the mixture discharge chamber formed by the cover plate 4 to the distributing spaces among the brush tufts. A tubular handle 29, also of rubber or similar material is provided with an integral crown plate 30 that encloses the metal cover plate 4', and the flange 31 of the crown plate is vulcanized or otherwise fixed to the brush head and cemented to the flanged cover plate. By this construction an interior mixing chamber 4 is provided for mixing water and liquid soap, and a liquid soap container or reservoir is provided between the crown plate and the cover plate which may be supplied with soap by removing the screw plug 32 mounted in the crown plate of the brush.

For supplying liquid soap to the mixing chamber a depressible disk valve 33 co-acts with a port in the cover plate 4, and a spring 34 between the disk valve and the brush head resiliently holds the valve in closed position.

A stem 35 of the valve projects through an opening in the crown plate 30, and a push button 36 on the stem exterior of the crown plate, by means of which the valve may be depressed to open position for the desired supply of liquid soap to the mixing chamber.

Water is supplied through the tubular handle from a supply hose attached to the nipple 37 at the outer end of the handle, and a gate valve 38 is mounted transversely of the tubular handle, near the brush head, to cut off the supply of water to the brush head. The gate valve is depressible against the tension of a spring, and the valve stem 39 projects through an opening in the valve portion of the handle and is provided with an exterior push button 40 to depress and open the valve against tension of spring 41 that tends to close the valve. The valve cavity is closed by a screw plug 42, and when the valve is opened water flows from the tubular handle through port 43 of the flanged cover plate 4 into the mixing chamber for mixture with the liquid soap, and for distribution through ports of the mixture to the bristles or tufts of the brush.

In Figure 5 the principles of the invention are physically embodied in a rubber, bath brush, or massage brush which is adapted as a hand implement for rubbing or scrubbing, and the rub-

4

bing or massaging fingers 44 of rubber are integral with a hollow circular head 45 having distributing ports 46 for the passage through this annular series of ports of liquid soap to the flexible fingers. The hollow head, which forms a soap container is closed by a cover plate 47 of suitable metal, and the cover plate together with the metal crown plate 48 provide a water reservoir that is supplied with water through the tubular handle 49. The liquid soap is supplied to its container 45 through an inlet opening that is normally closed by a plug 50.

The annular flange or circular wall 51 of the hollow head is fashioned with an interior annular groove to receive the united edges 52 of the cover plate and the crown plate as a means for rigidly mounting these assembled parts, and of course the tubular handle, which may be equipped with a water-control valve, is utilized in manipulating the implement.

For dispensing and distributing the water from the water reservoir within the crown plate, the cover plate, which forms the bottom of the water reservoir, at its center is provided with outlet ports 53 that open into a distributing chamber 54 that is provided by a depression in a central boss 55 projecting from the head 45.

This boss 55 is fashioned with spaced ports 56 that permit flow of water into the spaces within the fingers 44 located at the central portion of the head 45, and the liquid soap passing through ports 46 is mixed with the water passing through ports 56, for use in combination with the massaging fingers of the head.

Having thus fully described my invention, what I claim as new and desire to secure by Letters Patent is:

In a soap and water dispenser for a fountain brush having a mixture discharge chamber, a separate liquid soap container, a tubular handle forming a liquid soap chamber and a water conduit and extended through the container, the combination with a discharge nozzle having an outlet to the mixture discharge chamber and intersecting the tubular handle, said nozzle having spaced lateral ports, and said soap chamber having gravity feed ports open to the container, of a valve rod reciprocable in the tubular handle, manually operated means for reciprocating the rod, a pair of longitudinally spaced heads fixed on the rod, a spacing sleeve rigid with the rod and movable transversely through the nozzle, a pair of relatively movable disk valves on the rod located at opposite ends of the sleeve for coaction with the lateral ports, and a coiled spring interposed between each head and an adjoining valve for closing said valves against the ports.
